(57) **CLAIM**

The ornamental design for a digital camera, as shown and described.

DESCRIPTION

FIG. 1 is a front perspective view of a digital camera showing my new design;

FIG. 2 is a back perspective view thereof;

FIG. 3 is a front elevation view thereof;

FIG. 4 is a back elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is a front perspective view thereof, shown with the digital camera in condition of use; and,

FIG. 10 is a back perspective view thereof, shown with the digital camera in condition of use.

The broken lines depict portions of the digital camera that form no part of the claimed design.
